UNITED STATES PATENT OFFICE

2,369,254

FOOTWEAR

John Roman, Reading, Mass., assignor to Trim-mings, Inc., Lawrence, Mass., a corporation of Massachusetts

Application November 6, 1942, Serial No. 464,778

2 Claims. (Cl. 36—50)

This invention relates to improvements in footwear and more particularly to improvements in lacing fly closures for shoe uppers.

In most shoes metallic eyelets are employed at opposite sides of the lacing fly or throat opening of the upper for the reception of the lacing which is to close the fly when the shoe is being worn. These eyelets are expensive to manufacture and considerable expense is involved in the operation of inserting them, and consequently the use of the eyelets adds substantially to the cost of manufacturing the shoes.

One object of the present invention is to provide a lacing fly closure of simple and practical construction which is substantially less expensive than those which involve the use of metallic eyelets or the like.

It is also a particular object of the invention to provide a lacing fly closure which presents a neat and attractive appearance and which imparts novel and distinctive features of ornamentation to the shoe.

To the accomplishment of these objects, my invention, as herein illustrated, resides in a shoe provided with an upper or vamp having a fly or throat opening and having two flexible tapes or strips of textile material arranged adjacent to each side of the throat opening, the tapes extending lengthwise of the edges of the opening and being securely stitched to the upper and each tape having a plurality of loops formed as an integral part thereof and spaced lengthwise of the tape. As shown, these loops extend inwardly toward the lacing fly, the loops of one tape being disposed opposite those of the other tape, and a shoe lace is threaded through the loops for the purpose of closing the throat opening. Each tape, as herein illustrated, comprises a single body-forming strand or filler thread which, in the process of fabricating the tape, is folded in a single plane back and forth upon itself to form a series of bights which lie close together and extend alternately in opposite directions widthwise of the tape. The bights of this filler strand are bound together by means of one or more relatively small threads extending lengthwise of the tape which are interengaged with the bights or cross-stretches of the filler strand. At each of a series of regularly spaced intervals throughout the length of the tape one of the bights of the filler strand is made substantially longer than the others and these long bights extend beyond one edge of the tape to constitute the lacing-receiving loops.

The invention will now be described with reference to the accompanying drawing, in which

Fig. 1 is a fragmentary plan view of a shoe in which my invention is embodied;

Fig. 2 is a side elevational view of the shoe;

Fig. 3 is a plan view of a piece of the tape in which are formed the lacing loops which constitute part of the lacing fly closure;

Fig. 4 is a plan view of a portion of the upper 10 of the shoe showing the loop-forming tape secured thereto; and

Fig. 5 is a sectional view taken along the line V—V of Fig. 4.

Referring to the drawing, the shoe shown therein comprises an upper 6 having a lacing fly or throat opening 8. The fly or opening 8 extends from the top edge 10 of the upper forwardly to a point 12 located a substantial distance rearwardly of the toe end of the shoe, and the opening 8 is adapted to be maintained in a closed or partially closed condition by means of a lacing 14 which extends through a plurality of lacing loops 16 formed as integral parts of two tapes 18 which are located one at either side of the opening 8 and are firmly secured to the upper by a line of stitching 20 (Figs. 4 and 5).

The tapes 18 extend in directions lengthwise of the shoe and they are disposed in substantially parallel relation to the edges 22 of the upper which define the opposite sides of the fly or throat opening. Each tape 18 extends from the top edge 10 of the upper forwardly beyond the front end of the throat opening 8 substantially to the front extremity of the toe portion of the upper. The lacing loops 16 are spaced equal distances apart throughout the length of each tape and they extend in directions widthwise of the tape inwardly toward the lacing fly, the loops terminating short of the edges 22, however, so that the inner ends of the loops are spaced outwardly from the latter. As shown, the loops of each tape are disposed opposite the loops of the other tape.

The lacing 14 is threaded back and forth 45 through the opposed loops of the two tapes in a manner similar to that conventionally practised in shoes having lacing eyelets instead of loops, as clearly shown in Figs. 1 and 2 of the drawing.

It will be noted that inasmuch as the lacing loops terminate short of the edges of the fly or throat opening, the lacing overlaps the shoe upper at the opposite sides of the fly where it is engaged with the loops, and also that the lacing overlies the closed toe portion of the upper,

forwardly of the fly, where it is engaged with the loops in the portions of the tapes which extend into the toe of the shoe.

The tapes 18 may be made of strands of textile material knitted, woven, braided or otherwise united into a continuous fabric structure. As herein shown, the fabric structure consists of a single, relatively heavy, filler or body-forming strand 26 (Fig. 3) and two relatively light strands or threads 28 which are interengaged with the filler strand to form a fabric tape.

In making the tape, in the particular form herein illustrated, the filler or body-forming strand 26 is bent or folded back and forth upon itself in a single plane to form a series of folds or bights extending alternately in opposite directions crosswise of the tape, these bights being disposed in contiguous relation, and the two threads 28 are run lengthwise of the tape and interengaged with the folds or bights of the filler strand 26 so as to form, in effect, chain stitched seams binding the folds together to form a unitary fabricated tape. The folds or bights of the strand 26 are made of uniform length except that, at regular intervals throughout the length of the tape, they are made relatively long and caused to extend beyond one edge of the tape to constitute loops for receiving the lacing 14.

In making the shoe, a piece of tape long enough to extend from the top edge 10 of the upper to the toe end of the shoe is positioned upon the upper at the desired distance from the adjacent side of the fly or throat opening and is securely attached to the upper by means of one or more lines of stitching as, for example, the single line of lock stitches shown at 20, the individual stitches extending through the tape and through the upper. Another piece of tape of the same length is similarly applied and stitched to the opposite side of the lacing fly, the two pieces of tape being arranged with the lacing loops extending inwardly toward the fly. The lacing loops are thus adapted to function in substantially the same manner as conventional lacing apertures or eyelets. The loops being composed of flexible textile material, however, are consequently adapted to flex or bend freely lengthwise of the shoe and to yield or stretch to a certain extent and are thus enabled to adjust themselves to the lacing to make the upper more readily conformable to the contour of the foot. This will enhance the form-fitting characteristics of the shoe and make it more comfortable and serviceable in use. Moreover, the extension of the lacing closure into the toe portion of the upper, forwardly of the fly 8, provides a construction in which, by tightening the lacing, the upper may be caused to fit more snugly and conform better to the irregularities of foot contour in that locality. The expense of making and applying the loop-bearing tapes is considerably less than that involved in the manufacture of metallic eyelets and their insertion in the upper of a shoe and, consequently, a

shoe having a laced closure for its throat opening can be manufactured at a substantial reduction in cost over that of a shoe having conventional lacing eyelets and the shoe will present a distinctly novel and stylish appearance and will have outstanding features of ornamentation rendering it exceptionally attractive to a prospective wearer. Moreover, the stitching of the tape to the upper affords a practical, inexpensive and effective manner of securing the lacing loops to the shoe, it being obvious that the stitching serves also to bind together even more firmly the bights of the strand constituting the body portion of the tape. If desired, of course, the binding together of the body strands of the tapes, and the attachment of the tapes to the upper, may be made even more secure by the employment of additional lines of attaching stitches.

Having described my invention, what I claim as new and desire to secure by Letters Patent of the United States is:

1. In a shoe, the combination with an upper having a lacing fly or throat opening, of two tapes spaced outwardly from the edges of said throat opening and extending lengthwise of the shoe, each of said tapes comprising two strands, one of said strands forming a series of long loops and a plurality of short loops all extending widthwise of the tape and the other of said strands holding the loops of the first strand in assembled relation to provide a unitary fabricated structure, said short loops being arranged in groups interposed between adjacent long loops and said long loops terminating substantial distances outwardly of the edges of said opening and being disposed with both sides engaging the upper, and a line of stitching extending crosswise through both the long loops and the short loops and securing the tapes to the upper thereby adapting the loops to receive a lacing for maintaining said throat opening in a partially closed condition and holding the loops against the upper.

2. In a shoe, the combination with an upper having a lacing fly or throat opening, of two fabricated tapes extending along opposite sides of the throat opening, each of said tapes comprising a continuous strand lying throughout its length against the upper and forming a series of loops extending widthwise of the tape, and a second continuous strand extending lengthwise of the tape and forming a series of chain stitches encircling the cross-stretches of said loops and cooperating with said loops to constitute a textile fabric, said loops comprising relatively long loops terminating outwardly of the edges of said throat opening and relatively short loops spacing said long loops equal distances apart, lines of stitching securing said tapes to the upper, and a lacing threaded through said long loops, said lacing holding the loops against the upper and holding said throat opening in a partially closed condition.

JOHN ROMAN.
